Primary Examiner — John R Yeh(74) *Attorney, Agent, or Firm* — Kunzler Bean & Adamson, PC; Michael Bartholomew(57) **CLAIM**

The ornamental design for a mop head, as shown and described.

DESCRIPTION

FIG. 1 is a front, right and top perspective view of my new design for a mop head;

FIG. 2 is a rear, left and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, right and top perspective view of the mop head in an environmental setting;

FIG. 10 is an enlarged view of detail 10 indicated in FIG. 1; and,

FIG. 11 is an enlarged view of detail 11 indicated in FIG. 2. The dash-dash broken lines depict environment and portions of the mop head that form no part of the claimed design. The dot-dash broken lines in FIGS. 1-2 and 10-11 depict enlargement indications and form no part of the claimed design.
